ROLL DOWN NOSING

Paul C. Gebhard, Youngstown, Ohio, assignor to
Youngstown Manufacturing, Inc., Youngstown,
Ohio, a corporation of Ohio

Application April 29, 1950, Serial No. 9,572

Term of patent 14 years

(Cl. D54—2)

To all whom it may concern:

Be it known that I, Paul C. Gebhard, a citizen of the United States, residing at Youngstown, in the county of Mahoning and State of Ohio, have invented a new, original, and ornamental Design for a Roll Down Nosing, of which the following is a specification, reference being had to the accompanying drawing, forming a part thereof.

Figure 1 is a perspective view of a roll down nosing showing my new design in open position;

Figure 2 is a perspective view of the roll down nosing showing a portion thereof rolled down; and

Figure 3 is a perspective view of the roll down nosing showing two portions thereof rolled down.

I claim:

The ornamental design for a roll down nosing, as shown.

PAUL C. GEBHARD.
